UNITED STATES PATENT OFFICE.

BRYANT H. BLOOD, OF HARTFORD, CONNECTICUT, ASSIGNOR TO PRATT & WHITNEY COMPANY, OF NEW YORK, N. Y., A CORPORATION OF NEW JERSEY.

GAUGE BLOCK.

1,407,833.

Specification of Letters Patent. Patented Feb. 28, 1922.

Application filed June 28, 1919. Serial No. 307,459.

To all whom it may concern:

Be it known that I, BRYANT H. BLOOD, a citizen of the United States, residing at Hartford, in the county of Hartford and 5 State of Connecticut, have invented certain new and useful Improvements in Gauge Blocks, of which the following is a specification.

This invention relates to gauge blocks provided with opposite parallel flat faces at a predetermined distance apart. One object of the invention is to provide gauge blocks of this type with improved lateral surfaces which are adapted to be easily grasped without slipping and which have an improved 10 appearance. Another object of the invention is to provide an improved configuration at the edges of the block to prevent marring of or interference with the working faces.

20 In the accompanying drawing I have shown the preferred embodiment of the invention, but it will be understood that there may be variation, particularly as concerns the transverse shape.

25 Of the drawing:

Fig. 1 is a perspective view.

Fig. 2 is a plan view.

Fig. 3 is an enlarged transverse sectional view taken along the line 3-3 of Fig. 2.

30 Fig. 4 is a view similar to Fig. 3 but showing the effect of a bruise.

The drawing shows a gauge block B which is square, but it will be understood that I do not limit myself to this shape and that the 35 blocks may be made circular or otherwise. Each block has opposite parallel plane or flat end faces 1-1 which are at a predetermined distance apart. The blocks are very accurately constructed as concerns flatness 40 and parallelism of the surfaces and as concerns the length between them. The lengths are preferably either multiples or definite fractions, usually decimal fractions, of a predetermined unit of length. Ordinarily 45 a series of blocks is provided of which the several blocks have different lengths so that by combining a number of blocks with their end faces in engagement any desired length may be built up.

50 Gauge blocks of this type are intended for use in machine shops and other places where the hands of the user are apt to be coated with oil. In order to prevent the blocks from slipping in the hands of the user and 55 in order further to improve the appearance

of the blocks, I provide the lateral surfaces 2-2 thereof with a peculiar finish. As somewhat crudely illustrated in Fig. 3, each lateral surface of the block is roughened, being provided with a large number of minute 60 indentations and alternating elevations. In addition to the roughening of the surface by providing these indentations and elevations, the surface is further treated to give it a dull rather than a polished finish. Preferably 65 the major roughening of the block is effected by means of a sand blast process, and the dull finish is subsequently effected by means of a mud blast process. As the result of these two processes used successively, the block is roughened in such a way as to prevent its slipping in the hands of the user, and the roughened or uneven surface is given a dull finish which greatly improves its appearance.

70 Preferably, as illustrated in Fig. 3, the ends of the blocks are slightly beveled, an inclined surface 3 being provided adjacent the main surface 1 at each edge thereof. As shown in the drawing the included angle 75 between the beveled surface 3 and the end face 1 is a little less than 180°, being approximately 172°. It will be understood that I do not limit myself to this exact angle but it is essential that the angle be relatively 80 large, preferably being approximately that shown, and certainly not being less than 150°. It will be understood therefore that when I refer to slightly beveled surfaces I refer to surfaces at an angle of the order 85 indicated. The corners of the block between the beveled surfaces 3 and the lateral surfaces 2 are rounded as shown at 4. The beveling of the said surfaces adjacent the edges and the rounding of the corners serve to prevent any minor protrusions or burrs resulting from an accidental bruise, from projecting outward in such a way as to interfere with the proper engagement of the block 90 with another similar block.

95 Fig. 4 shows a block which has been slightly bruised, with the result that a small protrusion has been raised as shown at 5. It will be seen that on account of the slight beveling of the surface 3 this protrusion does not extend beyond the plane of the main face 1, and thus does not interfere with the proper engagement of the said face 1 with another flat face. It will be seen that 100 the angle between the surface 3 and the sur- 110

face 2 is much smaller than that between the surface 3 and the face 1, the result being that any bruise or protrusion is caused to occur at the smaller angle rather than at the 5 larger one. As shown, a protrusion 5 at the smaller angle is harmless whereas the same protrusion at the larger angle would interfere with the working face. Clearly if 10 the beveling was such that the two angles were the same the beveling would be of little use as there would be just as much danger of a protrusion at one angle as at the other.

What I claim is:

- 15 1. A gauge block provided with opposite parallel flat end faces and having sand blasted lateral surfaces whereby said surfaces are uniformly roughened, said sand blasted surfaces being mud blasted to give them a dull finish.
- 20 2. A gauge block provided with opposite parallel flat end faces and with slightly beveled surfaces at the edges of the end faces, the angle between each beveled surface and the end face being but a little less 25 than 180° and the angle between each

beveled surface and the corresponding lateral surface being a little more than 90° , the said beveled surfaces serving to prevent minor bruises or protrusions at the corners from interfering with the engagement of the 30 corresponding flat end face with another similar flat face.

3. A gauge block provided with opposite parallel flat end faces and with slightly beveled surfaces at the edges of the end 35 faces and with rounded corners between the beveled surfaces and the lateral surfaces, the angle between each beveled surface and the end face being but a little less than 180° and the angle between each beveled surface 40 and the corresponding lateral surface being a little more than 90° , the said beveled surfaces serving to prevent minor bruises or protrusions at the corners from interfering with the engagement of the corresponding 45 flat end face with another similar flat face.

In testimony whereof, I hereto affix my signature.

BRYANT H. BLOOD.
